Albert Rosenstein

BY Dumb H. Herr.

ATTORNEY.

UNITED STATES PATENT OFFICE.

ALBERT ROSENSTEIN, OF LANCASTER, PENNSYLVANIA.

DESIGN FOR AN UMBRELLA, PARASOL, OR CANE HANDLE.

No. 38,463.

Specification for Design.

Patented Feb. 19, 1907.

Application filed January 14, 1907. Serial No. 352,306. Term of patent 3½ years.

To all whom it may concern:

Be it known that I, ALBERT ROSENSTEIN, a citizen of the United States, residing at Lancaster, in the county of Lancaster and State of Pennsylvania, have invented a new, original, and ornamental Design for Umbrella, Parasol, or Cane Handles, of which the following is a specification, reference being had to the accompanying drawing, forming part thereof.

The figure is a view in side elevation of an umbrella, parasol, or cane handle, showing my new design.

I claim—

The ornamental design for an umbrella, parasol or cane handle, as shown.

ALBERT ROSENSTEIN.
